HAND-CART

Wilbur M. Huber, Cincinnati, Ohio, assignor to
Robbins & Huber, Inc., Cincinnati, Ohio, a corporation of Ohio

Application June 29, 1948, Serial No. 147,276

Term of patent 7 years

(Cl. D14—3)

To all whom it may concern:

Be it known that I, Wilbur M. Huber, a citizen of the United States, residing at Cincinnati, in the county of Hamilton and State of Ohio, have invented a new, original, and ornamental Design for a Hand-Cart, of which the following is a specification, reference being had to the accompanying drawings, forming a part thereof.

Figure 3 is a side elevation of the hand-cart with the retaining ring in extended position and a basket shown, for illustrative purposes only in broken lines in position on the cart.

I claim:

The ornamental design for a hand-cart, substantially as shown and described.

WILBUR M. HUBER.
